LOCKABLE HASP FASTENER

Albert J. Komenak, Stamford, Conn., assignor to
The Excelsior Hardware Company, Stamford,
Conn., a corporation of Connecticut

Application February 24, 1941, Serial No. 380,294

12 Claims. (Cl. 70—76)

This invention relates to hasp fasteners of the type which incorporate a hasp in the form of a rigid bail or draw loop pivotally hung on a toggle lever which in turn is pivotally mounted to be swung manually over a dead centering position for drawing and holding firmly together the separable edges of hinged together container parts such as the body and lid of an article of luggage, tool box, trunk or the like.

A lockable hasp fastener of this general type is disclosed in my earlier Patent No. 1,652,676. The present improvements aim to make certain parts of this earlier fastener stronger, more conveniently operable and more compactly organized through the provision of new and more advantageous features of construction.

One object of the invention is to impart more strength and rigidity to the end of the manually operated toggle lever which coacts with the usual leaf spring that serves to bias the toggle lever toward its limit positions in both directions of its swing.

A further object is to limit the swinging fall of the loop-like hasp to a forward or outward extending position when the fastener is open, instead of permitting such hasp to drop fully to a vertically depending position in close proximity to the front face of the container body as heretofore. This avoids having to reach to the rear of the hasp for first retrieving it from its down hanging position before it can be swung to a usable position for fastening, and hence increases the readiness with which the hasp can be manipulated by the user's fingers and flipped into engagement with the keeper shoulder preparatory to closing and locking the fastener.

A further object is, within the limited space available, to strengthen and render more rugged the lever carried striker engaged by the bolt of the lock and also to mount such striker more rigidly on the toggle lever.

A further object is to secure the lock case in place by means of the same fastening tongues and by means of the same assembly operation which attaches the key barrel supporting frame jacket to the mounting or escutcheon plate.

A still further object is to produce the keeper and its carried dowel tongue from a single sheet of metal drawn to dished formations which provide a draw shoulder to be engaged by the hasp loop and also provide the dowel tongue.

A still further object is to secure the before mentioned biasing spring on the escutcheon plate without the use of rivets, screws, or other extraneous fastening parts thereby to afford more room in the shallow interior of the lock case for the lock mechanism.

The foregoing and other objects of the present improvements will appear in greater detail from

the following description having reference to the accompanying drawing, wherein:

Fig. 1 is a front elevation of a lockable hasp fastener incorporating the present improvements.

Fig. 2 is an edgewise view looking from the left at Fig. 1 showing a portion of the container parts held together by my improved fastener.

Fig. 3 is a view drawn on an enlarged scale taken in section on the plane 3—3 in Fig. 1 looking in the direction of the arrows.

Fig. 4 is a fragmentary view of certain parts shown in Fig. 2 drawn on the same scale as in Fig. 3, the toggle lever and hasp being shown in opened position and in part broken away.

Fig. 5 is a bottom plan view looking at Fig. 4 from the plane 5—5.

Fig. 6 is a still further enlarged view showing fragments of parts in section on the plane 6—6 in Fig. 4 looking in the direction of the arrows.

Fig. 7 is a fragmentary view of the dowel tongue drawn on a larger scale than in Fig. 3.

Fig. 8 is a view taken partly in section on the plane 8—8 in Fig. 3, looking in the direction of the arrows.

Fig. 9 is a front view of the mechanism inside the lock case as viewed from the section line 9—9 in Fig. 8 drawn on a scale similar to Fig. 1.

10 and 11 represent vertical walls respectively of the body and lid of a trunk or other article of

30 luggage or, say, a container having a hinged cover such as a mechanic's tool box or the like. The keeper 12 is in the form of a hollow or dished section of drawn sheet metal which includes a margin portion 13 adapted to be secured broadside against a vertical wall of lid 11 by rivets or screws 14, and a seating portion 15 affording a keeper shoulder which contains the aperture 16 with which the hasp member, as hereinafter more fully described, retentively engages.

40 A mounting or escutcheon frame 20 includes a shallow dished plate drawn from sheet metal and adapted to be secured broadside against and fixedly to container body 10 by screws or rivets 21. The rearward disposed concavity afforded by

45 member 20 is occupied by a casing 22 of a lock mechanism designated as a whole by 23. This lock mechanism may be of any desired construction, as for instance that shown in Fig. 9 inclusive of a vertically slidably irregularly shaped

50 plate 24 having a tongue 18 which serves as the bolt of the lock. Bolt plate 24 is shown in Fig. 9 to occupy the full width of the lock case chamber and it, together with carried spring 19, is guided to move edgewise in paths unoccupied by stationary tangs 33 hereinafter referred to. This lock mechanism also includes a key barrel 25 in which

55 the key 26 is insertable as shown by broken lines in Fig. 2, and a leaf spring 19 carried by bolt plate 24 constantly urges plate 24 toward the right

60 in Fig. 9, whereby lug 36 on the edge of plate 24

becomes lodged either above or below casing abutment 36. Spring 19 diverges from plate 24 and extends past the opposite side of one of the tangs 35 to bear against a side wall of the lock case. The slotted rotatable barrel 25 guides the key 26 into cooperative relationship to said lock mechanism and has its front end exposed through the front of jacket structure 30. Barrel 25 extends rearward far enough to project into the interior of lock case 23 and if desired may be journaled in the rear wall 22 thereof as shown in Fig. 8.

The key barrel has its front end 27 reduced in diameter and rotatably supported in an aperture 28 contained in the front wall 29 of a frame jacket structure 30 whose side walls 31 at their lower ends support opposite ends, respectively, of a hinge pin 32. Side walls 31 are each provided with a pair of elongated tangs 33 which extend not only through closely fitting slots in the escutcheon plate 20 but continue rearward through the shallow depth of chamber in lock case 22 and then on through close fitting slots 35 in the rear wall of the latter. Against the back surface of case 22, tangs 33 are swaged over to fasten them against withdrawal from said slots as means for holding in common and solidly against escutcheon plate 20, the frame jacket 30 and the lock case 22, on respectively front and rear sides of the escutcheon plate. Lock case 22 has sufficient internal depth from front to back and sufficient internal width from side to side to house the lock mechanism shown in Fig. 9. The slots 35 in its rear wall are nearer together sidewise of the lock case than is the overall width of the lock case. Slots 35 furthermore are aligned respectively with the aforesaid four closely fitting slots or apertures for tangs 33 in the mounting frame or escutcheon plate 20 so that frame jacket 30 need be no greater in width than the mechanism containing chamber in the lock case. Also by this arrangement hasp arms 55, 55 are enabled to overlie at least a portion of the chamber in the lock case while, at the same time, flanking the frame jacket 30. In Fig. 8, the side walls 31 of jacket structure 30 will be observed to be nearer together than the side walls 60 of lock case 22 whereby the combined width of the jacket structure and the width of the hasp arms 55 which flank it need not exceed the overall width of the lock case.

Inside of frame jacket 30 a retainer plate 34 assists in supporting and retaining the key barrel, having for this purpose a bent metal formation most clearly shown in Fig. 8. The top wall 40 of jacket 30 has a rearward turned tongue 41 inclined somewhat downward for coacting with the dowel tongue 17 of keeper 12 to cam the latter into its receiving aperture 42 when lid 11 closes down against the body 10 of the trunk or other container. This serves to urge the front walls of said lid and body into true planar alignment and hold them thus even before the fastener is closed and locked.

Coming now to the swingable parts of the fastener, the manual or finger operated toggle lever 43 which I may refer to as the hasp operating handle or member is formed for the most part by drawing a sheet of metal to dished formation in a way to provide a front smooth surfaced wall section with the side walls 44 and the top wall 45. These top and side walls are integral and form a crackless junction at the upper end portion of toggle lever 43 which is pivotally supported on the mounting frame 20 by hinge pin 32 passing freely

through said side walls 44 of the lever and lodged in the side walls 31 of frame jacket 30.

A leaf spring 49 is secured against the front face of escutcheon plate 20 by striking from the metal of the latter a bump or boss 50 raised toward the front sufficiently to project through and fit a fastening hole in spring 49. This boss is then swaged over at 50 in the manner of a hollow rivet against the front face of the spring. Spring 49 coacts with the pivotally mounted end of toggle lever 43 as best shown in Figs. 3 and 4, wherefore it is clear that this spring yieldingly opposes shifting of lever 43 away from either of its positions shown in Fig. 3 or Fig. 4 because the arc of travel of the edge of the top wall 45 of toggle lever 43 necessitates rearward flexing displacement of spring 49 against the latter's resilient tendency to bias lever 43 into either one or the other of its positions in Fig. 3 or Fig. 4 as it swings within its range of positions below its horizontal position shown by broken lines in Fig. 3.

Lever 43 carries welded or otherwise firmly secured to it a striker confined to the rear side of the aforesaid front lever wall in the form of an integral angle piece or bracket 51 including a striker flange 47 or perforate tongue section adapted to enter and project through an aperture 39 in the plate wall of mounting frame 20 and which contains an aperture 52 one edge of which provides the strike surface 46 adapted to be engaged and retained by the lock bolt 24 when the latter is shot downward out of case 22 by turning key 26. Angle piece 51 further includes the mounting flange 48 which has substantial area of surface contact with the front wall of toggle lever 43 to which it is thus well adapted to be welded or otherwise secured affording great strength despite the limited space available at this point. This is important because at this point maximum strain is exerted upon the parts if attempt should be made to lift the manually operated finger piece 53 of the toggle lever when the latter is locked.

Also in the side walls 44 of lever 43 there is carried a pivot pin 54 which projects also through the hinge flanges 57 on the spaced arms 55 of the loop-like hasp 56, being headed over outside of the latter as a means of retaining this pivot pin in place. Hasp 56 may be formed from flat metal bent over to form said hinge flanges 57 and is provided at its looped opposite end, or nose, with the inward projecting short tongue 58 which is retentively received into aperture 16 in the keeper 12. The hasp arms 55 straddle the hasp operating member or lever 43.

Heretofore when a hasp of the nature of 56 has been pivotally swung from a toggle lever of the nature of 43, such hasp has been able to fall fully downward into a vertically depending position 56' as indicated by broken lines in Fig. 4. But by these improvements the hasp can not drop to this position which would be objectionable because requiring so much greater degree of manual swinging of the hasp in order to restore it to its broken line position 56'' in Fig. 3 preparatory to seating it upon the keeper 12. This objective is accomplished by striking laterally outward from the metal of the side walls 44 of the toggle lever two embossed stop projections, abutments or protuberances 59 which engage with the arms 55 of the hasp, respectively, and thus limit downward swing of the latter relative to toggle lever 43 to that relationship of these two parts shown in Fig. 4. Therein the hasp is angularly displaced upward from operating lever 43 and outstands from the front face of mounting plate 20 and from the

vertical wall of the container on which the same is mounted.

In the use of my improved fastener, the toggle lever 43 and hasp 56 will normally be found stably biased by spring 49 into their idle or non-working full line positions in Fig. 4 when the fastener is open. In fasteners not embodying certain of the present improvements the hasp would be found in the aforesaid fully fallen or vertically depending position 56' indicated for purposes of illustration only by broken lines in Fig. 4. This undesirable normal or fallen position of the open hasp can not obtain in the improved construction here shown because bumps 59 serve as stop means to limit the falling swing of the hasp relative to lever 43 and hence relative to the fastener frame plate 20 and container body 10.

To prepare the hasp for closure of the fastener it is first merely flipped backward counterclockwise into its broken line position in Fig. 3 accompanied if desired by lifting swing of toggle lever 43 higher than its range of working or hasp fastening positions, after which clockwise swinging of toggle lever 43 from its broken line position to its full line position in this figure will pull the hasp downward and its nose tongue 58 into retained occupancy of aperture 15 in the top seating wall of hollow keeper 12. In Fig. 3 it is seen that in completing the clockwise swinging of lever 43 hasp pivot 54 becomes slightly overcentered in relation to a projected straight line passing through lever pivot 32 and the point of bearing of the hasp nose on the seating surface of the keeper, which action assisted by the bias of spring 49 against lever 43, tends to keep these parts in their line position in Fig. 3 unaided by the lock bolt 24. Now, however, aperture 52 in striker flange 47 of angle member 51 is in position to receive lock bolt 24 which can be shot into said aperture by turning key 26. Upon retraction of bolt 24 by reverse turning of the key the toggle lever will again be freed and liftable to its full line position in Fig. 4 or broken line position in Fig. 3. This lifts hasp tongue 58 clear of keeper aperture 16 whereupon the hasp can be swung forward and clear of the keeper thus restoring the parts to their normal unfastened positions.

As various departures may be made within the scope of this invention from the exact forms arrangements and operation of the parts herein disclosed to illustrate the present improvements, the following claims will be understood to apply to and cover all substitutes and equivalents for such parts and functions that fairly fall within their terms.

I claim:

1. In a hasp fastener adapted to be carried by the vertical wall of a container having a hinged cover to be secured by said fastener, the combination with a mounting plate adapted to be fixed broadside against said container wall to present a vertically disposed face, of a manually swingable lever pivotally supported on said mounting plate to be swung through a range of working positions substantially lower than the horizontal position of said lever, a hasp carried by and pivotally connected to said lever to be swung upward and downward relatively thereto, and stop means positioned on said lever to be engaged by said hasp in a manner to limit downward swing of the latter to a position angularly displaced from said lever wherein the hasp is caused to outstand a substantial distance from both said vertical plate face and said vertical container wall when said lever occupies its said low range of working positions.

2. In a hasp fastener, the combination defined in claim 1, in which the said stop means comprises an abutment projecting from the said lever in the path of swinging movement of the said hasp.

5 3. In a hasp fastener, the combination defined in claim 1, in which the said lever includes a hollow section having a side wall bordering the interior thereof and flanking the path of swinging movement of said hasp, and the said stop means 10 comprises an abutment formed by a portion of the material of said side wall projecting outward therefrom into said path of swinging movement of the hasp.

4. In a hasp fastener, the combination defined 15 in claim 1, in which the said lever includes a hollow section having a thin side wall bordering the interior thereof and flanking the path of swinging movement of the said hasp, and the said stop means comprises a protuberance embossed outward from said material of said side wall in the path of swinging movement of the hasp.

5. In a lockable hasp fastener, the combination 25 with a frame including a mounting plate containing an aperture, of a hasp, a lock including a bolt adapted to be shot to and retracted from a locking position across said aperture at the rear of said mounting plate, a lever swingably carrying said hasp at the front of said plate pivotally mounted on said frame in the neighborhood of said lock 30 having a smooth surfaced solid wall section throwable into proximity to said aperture, and a striker comprising an integral, angle piece confined to the side of said solid wall section that faces said aperture and fixedly secured thereto including a perforate tongue section disposed to enter said aperture to be lockingly engaged by said bolt.

6. In a lockable hasp fastener, the combination 40 of, a loop hasp, a mounting frame having a front wall containing spaced apertures, lock mechanism at the rear of said frame including a locking bolt, a hollow lock case having sufficient internal depth from front to back and sufficient internal width from side to side to house said mechanism and having a rear wall containing slots located nearer together sidewise of said lock case than said width of the lock case respectively aligned with said apertures and separated from the latter by a distance equal to said depth of the lock case, a jacket 50 structure no greater in width than said lock case at the front of said frame wall, a hasp operating member in part straddled by said hasp and operably associated with said bolt of the lock mechanism and pivotally mounted on said jacket structure at the front of said mounting frame, and fastening tangs fixedly carried by said jacket structure located nearer together than said width of the lock case and projecting rearward from said jacket structure through said apertures respectively and spanning said depth of the lock case and extending rearward into said slots in said rear wall of the lock case, said tangs being fastened against withdrawal from said slots in a manner to hold both said lock case and jacket structure in 60 fixed relation to said mounting frame, whereby the overall width of said jacket structure may be narrower than said width of the lock case for compacting the combined overall width of said jacket structure said hasp and said member.

70 7. In a lockable hasp fastener, the combination defined in claim 6, in which the said lock case has side walls and the said jacket structure has side walls nearer together than said side walls of the lock case, and the said fastening tangs 75 are formed by straightaway rearward continua-

tions of the material of said side walls of the jacket structure.

8. In a lockable hasp fastener, the combination of, a hasp having laterally spaced side arms, a mounting frame having a front wall containing laterally spaced apertures, a lock case at the rear of said frame wall forming a hollow chamber wider than the lateral space between said apertures and having a rear wall containing slots respectively aligned with said apertures and separated from the latter by a distance equal to the depth of said chamber, a frame jacket standing forward from said frame wall to be flanked laterally by said hasp arms, said jacket being narrower than said chamber so that said hasp arms may overlie at least a portion of the width of said chamber, fastening tangs fixedly carried by said frame jacket projecting rearward through said apertures respectively and through said chamber and extending rearward into said slots, said tangs being fastened against withdrawal from said slots in a manner to hold both said case and said jacket in fixed relation to said mounting frame, and mechanism within said chamber for locking said hasp including shiftable parts confined to paths of movement unoccupied by said tangs.

9. In a lockable hasp fastener, the combination of, a looped hasp having side arms, a mounting frame plate having a front wall containing laterally spaced apertures, a lock case at the rear of said frame wall forming a hollow chamber wider than the lateral space between said apertures and having a rear wall containing slots respectively aligned with said apertures and separated from the latter by a distance equal to the depth of said chamber, a frame jacket standing forward from said frame wall to be flanked laterally by said hasp arms, said jacket being narrower than said chamber so that said hasp arms may overlie at least a portion of the width of said chamber, fastening tangs formed by straightaway rearward continuations of the material of said frame jacket projecting rearward through said apertures respectively and through said chamber and extending rearward into said slots, said tangs being fastened against withdrawal from said slots in a manner to hold both said case and said jacket in fixed relation to said mounting frame, and lock mechanism within said chamber for locking said hasp including shiftable parts confined to paths of movement unoccupied by said tangs.

10. In a lockable hasp fastener, the combination of, a hasp having swingable laterally spaced side arms, a mounting frame having a front wall containing laterally spaced apertures, a lock case at the rear of said frame wall forming a hollow chamber wider than the lateral space between said apertures and having a rear wall containing slots respectively aligned with said apertures and separated from the latter by a distance equal to the depth of said chamber, a frame jacket standing forward from said frame wall to be flanked laterally by said hasp arms, said jacket being narrower than said chamber so that said hasp arms may overlie at least a portion of the width of said chamber, a hasp operating handle pivotally mounted on said frame jacket between said hasp arms and pivotally connected to the latter, fastening tangs fixedly carried by said frame jacket projecting rearward through said apertures re-

spectively and through said chamber and extending rearward into said slots, said tangs being fastened against withdrawal from said slots in a manner to hold both said lock and said jacket in fixed relation to said frame wall, and mechanism within said chamber for locking said hasp operating handle including shiftable parts confined to paths of movement unoccupied by said tangs.

11. In a lockable hasp fastener, the combination of, a hasp having swingable laterally spaced side arms, a mounting frame having a front wall containing laterally spaced apertures, a lock case at the rear of said frame wall forming a hollow chamber wider than the lateral space between said apertures and having a rear wall containing slots respectively aligned with said apertures and separated from the latter by a distance equal to the depth of said chamber, a frame jacket standing forward from said frame wall to be flanked laterally by said hasp arms, said jacket being narrower than said chamber so that said hasp arms may overlie at least a portion of the width of said chamber, a hasp operating handle pivotally mounted on said frame jacket between said arms of the hasp and pivotally connected to the latter, fastening tangs fixedly carried by said frame jacket projecting rearward through said apertures respectively and through said chamber and extending rearward into said slots, said tangs being fastened against withdrawal from said slots in a manner to hold both said lock and said jacket in fixed relation to said frame wall, and mechanism within said chamber for locking said hasp operating handle including a locking bolt comprising a tongued plate occupying substantially the full width of said chamber shaped to be movable edgewise therewithin free of interference by said tangs.

12. In a lockable hasp fastener, the combination of, a hasp having swingable laterally spaced side arms, a mounting frame having a front wall containing laterally spaced apertures, a lock case at the rear of said frame wall forming a hollow chamber wider than the lateral space between said apertures and having a rear wall containing slots respectively aligned with said apertures and separated from the latter by a distance equal to the depth of said chamber, a frame jacket standing forward from said frame wall to be flanked laterally by said hasp arms, said jacket being narrower than said chamber so that said hasp arms may overlie at least a portion of the width of said chamber, a hasp operating handle pivotally mounted on said frame jacket between said arms of the hasp pivotally connected to the latter, fastening tangs fixedly carried by said frame jacket projecting rearward through said apertures respectively and through said chamber and extending rearward into said slots, said tangs being fastened against withdrawal from said slots in a manner to hold both said lock and said jacket in fixed relation to said frame wall, and mechanism within said chamber for locking said hasp operating handle including a locking bolt movable parallel with said rear wall of the lock case at one side of one of said tangs, and a leaf spring carried by said bolt within said chamber diverging from the latter and reaching past the other side of said one of said tangs.

ALBERT J. KOMENAK.
